UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

METHOD OF AND APPARATUS FOR TREATING TRANSPARENT MATERIAL.

Application filed June 25, 1923. Serial No. 647,580.

To all whom it may concern:

Be it known that I, WILLARD E. SWIFT, a citizen of the United States, residing at Worcester, in the county of Worcester and 5 Commonwealth of Massachusetts, have invented a new and useful Improvement in a Method of and Apparatus for Treating Transparent Material, of which the following, together with the accompanying drawings, is a specification.

The present invention relates to the treatment of transparent material for the purpose of reducing the glare, or reflection of light, from its surface. The invention is 15 particularly applicable to the treatment of such material as is used for the transparent patches or panels of so-called window envelopes,—i. e., the type of envelope having an opening therein over which is cemented 20 a covering of glassine paper or other transparent or semi-transparent material.

In window envelopes as thus manufactured, a troublesome feature is the glare, or reflection of light, from the surface of the 25 transparent patch material, this giving rise to objection on the part of those required to handle numbers of such envelopes, as for instance, in the sorting of mail, particularly when the light falls at a small angle from 30 the plane of the surface. The reduction or elimination of this glare, without substantial sacrifice of the transparency of the panel material, is the primary object of the present invention, the same involving the 35 subjection of the material, preferably before cutting it into patches, to an abrading action adapted to produce a matt or substantially glareless surface.

The essential features of this treatment, 40 together with one form of apparatus for effecting the same, are fully described hereinafter, reference being had to the accompanying drawings, wherein—

Fig. 1 is a view in elevation of apparatus embodying the invention.

Fig. 2 is a transverse sectional view of said apparatus.

Fig. 3 is a fragmentary enlarged sectional view, substantially on the line 3—3 of Fig. 50 1.

Fig. 4 is a fragmentary enlarged elevation, as viewed from the left hand side of Fig. 1.

Fig. 5 is a fragmentary enlarged section- 55 al view, substantially on the line 5—5 of Fig. 1.

Figs. 6, 7 and 8 are enlarged fragmentary 60 sectional views, taken substantially on the lines 6—6, 7—7 and 8—8, respectively, of Fig. 2.

Fig. 9 is an enlarged detail view of cer- 65 tain driving mechanism for the machine, and

Fig. 10 is an enlarged sectional view of the driving parts of a roll or spindle on 70 which the treated material is accumulated.

Like reference characters refer to like 75 parts in the different figures.

As best shown in Figs. 1, 2 and 9, the 80 frame of the machine is constituted by a pair of spaced upright substantially annular members 1, 1, having inwardly disposed standards 2, 2, the latter providing bearings for a centrally disposed shaft 3. A cylindrical drum 4, Figs. 2, 3 and 6, is connected 75 to rotate with the shaft 3 by means of spokes 5, 5, said drum lying wholly between the frame members 1, 1, with the inner peripheries of said parts substantially flush, as shown in Figs. 3, 5 and 6, thus permitting 85 the use of annular plates 6, 6 secured to said frame members and bearing against said drum to provide a substantially dust tight running joint between said parts.

As shown in Figs. 1 and 9, the drum 4 is 90 rotated from a motor or other driving device 7, the shaft 8 of which carries a worm 9 in mesh with a worm gear 10 on a counter- 95 shaft 11; a pulley 12 on said countershaft 11 has a belt connection 13 with another pulley 14 on the outer end of shaft 3. The frame members 1, 1 each provide upper and lower lateral extensions 15, 15 and 16, 16, the former being slotted at 17 to provide ro- 100 tative support for a supply spool or roll 18 of the material to be treated, and the latter providing suitable bearings 19, 19, Fig. 10, for the driving devices of a second spool or roll on which said material is accumulated after passage around the drum 4.

The driving shaft 8 also carries a sprocket wheel 20, having a sprocket chain connection 21 with a sprocket wheel 22 on shaft 23, Figs. 1, 2 and 8. The shaft 23 carries a driving sprocket 24 for a chain 25 which 105 serves for the actuation of the takeup spool,

as well as for the actuation of the abrading and brushing instrumentalities of the machine, said chain 25 being operatively associated, respectively, with a sprocket 26 of the takeup mechanism, Fig. 10, a sprocket 27 of the abrasive supply mechanism, Fig. 5, a sprocket 28 of the reciprocatory abrading shoes, Fig. 3, and sprockets 29 and 30 of the brushing mechanisms shown in Figs. 6 and 10. 7.

The hub of the sprocket 27 provides a bevel gear 31 that meshes with another bevel gear 32 on a short vertical spindle 33, the latter carrying a driving plate 34 which is used to impart agitation to a box or container 35 for abrasive material, such as powdered pumice, zinc oxide, or the like. To this end, as shown in Fig. 5, a rod or link 36 connects the plate 34 with said box, the latter being continuously shaken thereby so as to discharge its contents through a screened bottom 37 directly onto the web of material that is carried by the drum 4. Plates 38 attached to said box, are of sufficient width to overlie the frame members 1, thus providing a shield against the escape of the abrasive powder, and the supporting bars 39, 39 of said box which extend between the frame members 1, 1, as shown in Fig. 2, are respectively equipped one with a plate 40 having a flexible strip 41 bearing against drum 4, and the other with a removable cover 42, extending for a considerable distance to inclose the abrading devices. In this way, a complete inclosure is formed to prevent the escape of the powdered abrasive material, the side walls of which are constituted by the inner faces of frame members 1, 1, the outer wall by the cover 42, and the parts associated with box 35, and the inner wall by the drum 4 itself, in conjunction with the plates 6, 6. One end wall for this inclosure is constituted by the plate 40, and at the other or lower end, the inclosure is connected by a passage 43 with an exhaust channel 44, the latter providing suitable means, not shown, for drawing off all the dust and powdered material that results from the abrading treatment. Such treatment is effected by rubbing the surface of the material, during its travel on the drum 4, with the abrasive powder that is introduced from the box 35, a plurality of rubbing devices being employed, each preferably consisting of a block 45 having a facing 46 of leather, or other suitable material, as shown in Fig. 3. Each block 45 is carried by a reciprocatory bar 47, the latter being slidable longitudinally in guiding members 48, 48 that are laterally received in enlarged openings 49 of the frame members 1, 1. Springs 50, 50, acting on said guiding members 48, 48, are employed to draw each rubbing device inwardly, thereby to press yieldingly against the sur-

face of the material on drum 4. Each bar 47, on its forwardly projecting end, has a pin 51, said pins 51 being engaged in pairs, as shown in Fig. 4, by the slotted ends of rocking levers 52, 52; the latter, here shown as two in number, have their arms 53, 53 connected by a link 54, whereby to transmit movement from one to the other. One of said levers 52 provides a roll or follower 55 which is engaged by a track cam 56 secured to the rod or sprocket 28. In this way, the rotation of the sprocket 28 is caused to impart a reciprocatory movement to all of the bars 47, it being noted that adjacent rubbing blocks 45 move oppositely so as to balance and thereby nullify the forces that would otherwise tend to deflect the travelling material laterally. To prevent access of the abrasive powder to the bearing surfaces, suitable shields 57, 57 are provided for the retention of spring pressed pads 58 in wiping contact with each bar 47.

As shown in Figs. 2 and 6, provision is made for brushing the surface of the travelling material after its subjection to the rubbing action of the first pair of shoes or blocks 45, the sprocket wheel 29 for this purpose being secured to a shaft 59 which is journalled in suitable bearings 60, 60 provided by the frame members 1, 1. The shaft 59 carries a cylindrical brush 61, the action of which against the travelling web is to dislodge and remove powder and dust resulting from the first abrasion, said powder and dust being withdrawn from the inclosure through the passage 43. As before, the bearing surfaces are protected from dust by the devices 57 and 58, above described.

Additional brushing devices are provided for action on the material after the final abrasion thereof, such devices, as indicated at 62 and 63 respectively, Figs. 2, 7 and 8, being of substantially the same form as the brush 61, one being carried by a shaft 64, to which the sprocket 30 is secured, and the other being carried by shaft 23, which acts as the actuator for the chain 25. These two devices, as shown, are preferably rotated in opposite directions, the more thoroughly to remove from the surface of the material all of said powder and dust, the latter being drawn off, as heretofore described, through the exhaust channel 44. The web thus treated is guided off the drum by a roller 65 and thence is wound up on a spool or cylinder 66, Fig. 10, that derives its rotation in the following manner from sprocket 26.

The sprocket 26 is secured to a member 67, which is free to turn on a shaft 68, the latter being journalled in the bearing 19 provided by the front frame member 1. The rotation of sprocket 26 and member 67 is transmitted in greater or less degree to the shaft 68 by a friction clutch connection 69 between member 67 and a mem-

ber 70, keyed to said shaft. The spindle 71 of spool 66 has one end receivable in a slot 72 formed in the inner end of shaft 68, said parts being held together, for rotation in unison, by a removable pin 73. The other end of spindle 71 is supported by a recessed member 74, in axial alinement with the shaft 68, and journalled in the other bearing 19, this construction permitting the substitution of one spool for another following the accumulation of a sufficient amount of treated web thereon. The friction clutch connection 69 permits the necessary slippage between the driving and driven parts as the diameter of the accumulating roll of web material on the spool 66 gradually increases. The connection of the spool or cylinder 66 to its spindle 71 is by a plurality of pivotally mounted 20 spring pressed pawls or dogs 75, 75, Figs. 2 and 10, carried by said spindle and engaging the inner periphery of the spool, to permit removal of the spool from the spindle and to adapt the latter to the driving of spools of different internal diameters.

I claim,

1. In apparatus of the class described, means for moving a web of transparent material longitudinally, means for depositing abrasive powder on said moving web, and means for alternately rubbing and brushing the surface on which said abrasive powder is deposited.

2. In apparatus of the class described, means for moving a web of transparent material longitudinally, means for supplying abrasive material to said moving web, and means for transversely rubbing the surface to which said material is supplied.

3. In apparatus of the class described, an abrading chamber, means for moving transparent material progressively through said chamber, means for supplying abrasive material thereto, and means in said chamber for alternately rubbing and brushing the surface of said material.

4. In apparatus of the class described, an abrading chamber, means for moving transparent material through said chamber, means for supplying abrasive powder on the surface of said transparent material, and means for rubbing said surface with said powder in a direction transverse to the movement of said transparent material.

5. In apparatus of the class described, an abrading chamber, means for moving a web of transparent material therethrough, and means for subjecting said web in said chamber to abrasive action by transverse rubbing thereto.

6. The herein described method of treating transparent material to render its surface matt, which consists in applying abrasive powder to said surface, and then alternately rubbing and brushing the same.

7. The herein described method of treating a moving web of transparent material, which consists in applying abrasive powder to its surface and then rubbing said surface in directions transverse to the movement of said web.

8. The herein described method of treating a moving web of transparent material to render its surface matt, which consists in applying abrasive powder to said surface, and then rubbing the same in opposite directions transversely to the movement of said web.

9. In apparatus of the class described, a rotary member for procuring movement of a web of transparent material, means cooperating with said member to provide a peripheral abrading chamber through which said material is moved, means for supplying abrasive powder to the material in said chamber, and means for alternately rubbing and brushing the surface of the material as it moves through said chamber.

10. In apparatus of the class described, a rotary member for procuring movement of a web of transparent material, means cooperating with said member to provide a peripheral abrading chamber through which said material is moved, means for supplying abrasive powder to the material in said chamber, and means in said chamber for alternately rubbing and brushing the material on the periphery of said rotary member.

11. In apparatus of the class described, a rotary member for procuring movement of a web of transparent material, means cooperating with said member to provide a peripheral abrading chamber through which said material is moved, means for supplying abrasive powder to the material in said chamber, means for alternately rubbing and brushing the surface of the material as it moves through said chamber, and means for exhausting the products of abrasion from said chamber.

12. In apparatus of the class described, means for moving a web of transparent material longitudinally, means for supplying abrasive material to said moving web, and means for transversely rubbing the surface to which said material is supplied, said means comprising laterally reciprocated members actuated by a link motion.

13. In apparatus of the class described, means for moving a web of transparent material longitudinally, means for supplying abrasive material to said moving web, and means for transversely rubbing the surface to which said material is supplied, said means comprising laterally reciprocated blocks spring pressed against said surface.

Dated this 18th day of June, 1923.

WILLARD E. SWIFT.
